Primary Examiner — Cynthia Underwood*(74) Attorney, Agent, or Firm* — Ohlant, Greeley, Ruggiero & Perle, L.L.P.(57) **CLAIM**

The ornamental design for a vessel, as shown and described.

DESCRIPTION

FIG. 1 is a top perspective view of a vessel of the present disclosure;

FIG. 2 is a bottom perspective view of the vessel of FIG. 1;

FIG. 3 is a first side view of the vessel of FIG. 1;

FIG. 4 is a second side view of the vessel of FIG. 1;

FIG. 5 is a third side view of the vessel of FIG. 1;

FIG. 6 is a fourth side view of the vessel of FIG. 1;

FIG. 7 is a top view of the vessel of FIG. 1;

FIG. 8 is a bottom view of the vessel of FIG. 1;

FIG. 9 is a front view of a cross section taken along line 9-9 of the vessel of FIG. 7;

FIG. 10 is a perspective view of a cross section taken along line 10-10 of the vessel of FIG. 7; and,

FIG. 11 is a perspective view of the vessel of FIG. 1 shown in use.

The broken lines in the drawings illustrating environmental structure or boundaries is for illustrative purposes only and forms no part of the claimed design.
